UNITED STATES PATENT OFFICE.

HARRISON H. ROUNTREE, OF CHICAGO, ILLINOIS.

DESIGN FOR A SPROCKET-WHEEL CHAIN-GUARD.

SPECIFICATION forming part of Design No. 27,389, dated July 20, 1897.

Application filed June 9, 1897. Serial No. 640,074. Term of patent 3½ years.

To all whom it may concern:

Be it known that I, HARRISON H. ROUNTREE, a citizen of the United States, and a resident of Chicago, in the county of Cook and State 5 of Illinois, have invented and produced a new, useful, and original Design for Sprocket-Wheel and Driving-Chain Guards or Shields for Bicycles, of which the following is a specification.

10 In the accompanying drawings, Figure 1 is a perspective view of a guard or shield embodying my design, and Fig. 2 is a transverse sectional view thereof on the line 22 of Fig. 1.

A guard or shield of my design consists of 15 a marginal frame A, which is provided with flange A', projecting laterally therefrom in such manner that it will cover the driving-chain when said guard or shield is applied to a bicycle. The space within the marginal 20 frame A is occupied by a light open-work web A², in which is formed a suitable open-

ing or openings adapted to receive the parts of the bicycle when said guard or shield is applied thereto.

The essential features of my present invention consist in the contour of the shield or guard and in the configuration of the open-work web, they being made to represent the wing of a bird. 25

I claim—

30 The design for a sprocket-wheel and driving-chain guard or shield for bicycles, substantially as herein shown and described.

In testimony that I claim the foregoing as my invention I have hereunto set my hand, 35 this 7th day of June, 1897, in the presence of two witnesses.

HARRISON H. ROUNTREE.
